UNITED STATES PATENT OFFICE.

JOHN JACOBSON, OF NEW YORK, N. Y., ASSIGNEE, BY MESNE ASSIGNMENTS, TO WEAVE-PRINT COMPANY, A CORPORATION OF NEW YORK.

PROCESS OF TRANSFERRING DESIGNS TO CYLINDRICAL SURFACES.

No. 908,268.

Specification of Letters Patent.

Patented Dec. 29, 1908.

Application filed January 16, 1905, Serial No. 241,334. Renewed November 2, 1908. Serial No. 460,766.

To all whom it may concern:

Be it known that I, JOHN JACOBSON, of New York, in the county of New York and State of New York, have invented an Improvement in Processes of Transferring Designs to Cylindrical Surfaces, of which the following description, in connection with the accompanying drawings, is a specification.

10 The present invention relates to a process of producing a printing roller, the purpose being to obtain a roller having a printing surface capable of transferring to the printed material an exact reproduction of a given design, the process of producing the roller being a photographic process.

In carrying out the invention, a flat plate is produced with a relief surface in the form of a design, it being essential that the two 20 ends of the design should exactly match for some little distance. For example, if the design has been photographed from a model liable to distortion, such, for example as lace or other fabric, it is necessary to 25 arrange for an exact correspondence of the design at one end of the plate with that of the other. This plate is made of yielding material so as to be capable of transferring a coating, such as an acid resist, to a smooth, 30 hard surface, as that of a roller.

In accordance with the process involving the present invention the surface of the plate is inked, *i. e.* coated with the substance to be transferred such as acid resist, and the printing roller which is to be produced is rolled 35 over the inked plate, so that the resist is transferred to the surface of the roller in the form of the design. The roller can then be completed by any well-known etching 40 process.

It is essential, however, that the design should extend completely around the roller with no visible break or variation, and this is accomplished, as follows. As previously 45 stated the flat plate is so prepared that the units of the design near one end will exactly match or conform to those at the other end, and the plate is made somewhat longer than the periphery of the roller to which the 50 design is to be transferred.

The roller, so positioned as to stand exactly at a right angle to the design on the plate, is then let down upon the surface of

the plate and rolled along the same for a little more than one complete revolution. 55 This causes the ends of the transfer to overlap, but as the design at one end of the plate exactly corresponds to that at the other, the units will fall one over another, with no visible line of junction. Since it is impracticable, especially in a design which constitutes a copy of a fabric, to make the circumference of the roller of the exact size to take in a definite number of repetitions of the units of the design, so that the matched 60 ends will overlap, as described, the peripheral velocity of the roller is slightly varied from normal, during its complete revolution, *i. e.* during that part of its travel in which the design is transferred completely around the roller before overlapping. 70 If, for example, the distance between the exactly matched parts of the design, is slightly less than the distance around the roller, the roller is given a revolving movement slightly in excess of its normal rolling movement, sufficient, of course, merely to cause the part first transferred to finally reach a position where it will exactly match the design at the other end of the plate. If, 75 on the contrary, the distance between the matched parts is greater than the distance around the roller, the revolving movement is retarded.

In order to fully illustrate the process, 85 conventional drawings are annexed hereto, in which—

Figure 1 represents a roller and a plate at the beginning of the process; and Fig. 2 90 the same at the end of the process.

At the beginning of the process, the roller *a* is let down into contact with the surface of the plate, being shown as mounted on supports *b* indicated as pivoted at *b*², so that, by a movement on the pivot, the roller can be 95 lowered from a point above the plate into contact with the surface of the plate. The roller is then rolled along into contact with the surface to transfer the design, and is lifted from the plate by a corresponding support *b* at the opposite end shortly after the two ends of the design overlap.

The peripheral velocity of the roller may be varied from normal, as, for example, by means of a gear *c* and rack *d*, the latter being 105 longitudinally moved in either direction, it

being obvious that if it is moved in the same direction as the travel of the roller, the rate of rotation will be decreased, and vice versa.

Since the transfer of the acid resist to the surface of the roller is not the final step in the process, the amount of variation in the peripheral speed of the roller may be readily determined by experiment, the resist being washed off after each trial. The rate of rotation of the roller may be easily controlled by the use of an apparatus which forms the subject-matter of an application filed jointly July 25, 1904, by John Jacobson and John Tooker, Ser. No. 218,170, such apparatus, however, forming no part of the present invention.

The overlapping parts of the design are of very slight extent and are transferred respectively as the roller comes into contact with the plate and is lifted out of contact therewith—in other words where the impression is lightest; and the double impression therefore does not transfer any more material than the single impression in the body of the design where the pressure is greater.

I have found from practical tests, that it is possible, by this process to transfer a design to a cylindrical surface with such accuracy that it is impossible to detect any imperfection, or to discover the part corresponding to the meeting point of the ends of the design, even by the aid of a powerful magnifying glass. It is thoroughly practicable, therefore, to transfer, after any suitable preliminary photographic process of obtaining a flat plate, the most delicate de-

signs to cylindrical surfaces for printing purposes; and at far less expense than is possible by a mechanical process.

What I claim is:

1. The herein described process of transferring a design to a cylindrical surface which consists in forming on a plate a design in which the units of the design near one end exactly match the units of the design near the other end; inking said plate; rolling the cylindrical surface more than a complete revolution in contact with said plate; and decreasing the pressure of the cylindrical surface against the plate at the beginning and end of the rolling movement where the design parts overlap on the cylindrical surface.

2. The herein described process of transferring a design to a cylindrical surface which consists in forming on a plate a design somewhat longer than the circumference of the surface to which it is to be transferred and with the units of the design near one end exactly matching those near the other; inking said plate; rolling the cylindrical surface along the inked surface of said plate in peripheral contact therewith; and varying the peripheral velocity of said surface from normal during the period of rolling contact.

In testimony whereof, I have signed my name to this specification in the presence of two subscribing witnesses.

JOHN JACOBSON.
